UNITED STATES PATENT OFFICE.

MORRIS P. HOLMES, OF CLAREMONT, NEW HAMPSHIRE, ASSIGNOR TO SULLIVAN MACHINERY COMPANY, OF CLAREMONT, NEW HAMPSHIRE, A CORPORATION OF MASSACHUSETTS.

MINING-MACHINE.

1,303,797.

Specification of Letters Patent. Patented May 13, 1919.

Continuation in part of application Serial No. 833,782, filed April 22, 1914. This application filed August 31, 1914. Serial No. 859,280.

To all whom it may concern:

Be it known that I, MORRIS P. HOLMES, a citizen of the United States, and a resident of Claremont, county of Sullivan, and State of New Hampshire, have invented an Improvement in Mining-Machines, of which the following description, in connection with the accompanying drawings, is a specification, like characters on the drawings representing like parts.

This invention relates to mining machines, and more particularly, though not exclusively, to machines of the chain cutter type, and will be best understood by reference to the following specification, when taken in connection with the accompanying drawings of one specific embodiment thereof, while its scope will be more particularly pointed out in the appended claims.

20 In the drawings:

Figure 1 is a plan of one form of mining machine embodying my invention with the cover removed;

Fig. 2 is a side elevation of the same;

25 Fig. 3 is a sectional view on line 3—3 of Fig. 1;

Fig. 3^a is a central longitudinal section taken through the rear portion of the machine and constituting in effect an extension 30 of the section shown in Fig. 3.

Fig. 4 is a detail plan view on an enlarged scale, partly in section, of the mechanism for operating the cutter bars;

Fig. 5 is a detail, sectional view on an enlarged scale on line 5—5 of Fig. 1;

Fig. 6 is a detail, plan section on an enlarged scale on line 6—6 of Fig. 2;

Fig. 7 is a detail sectional view on line 7—7 of Fig. 4;

40 Fig. 8 is a detail elevation of an enlarged scale on one of the friction clutches;

Fig. 9 is a detail plan of the parts shown in Fig. 8;

Fig. 10 is a plan illustrating diagrammatically one mode of operation of the machine; and

Fig. 11 is a similar plan illustrating diagrammatically another mode of operation of the machine.

50 Referring to the drawings, and to the embodiment of my invention which I have selected for illustration, I have there shown a mining machine comprising a main portable support or body 12, the same herein

comprising longitudinal supporting bars 13 55 and 14, the latter extending the full length of the machine and having secured to their upper faces flat guide plates 15 and 16, on which a machine frame rests, and is adapted to slide, as will be described presently. 60

The bed may be supported at its forward end upon a suitable truck frame 17, and at its rear end on a similar truck frame 18, the former being journaled on axles 19 and 20, provided with wheels 21 and 22, while the 65 rear truck frame is journaled on axles 23 and 24, having secured thereto wheels 25 and 26. The wheels are adapted to travel upon rails of a suitable trackway 27, which will be laid adjacent the coal face or rib to be 70 cut, either parallel with the same or at right angles thereto, or in any other desired relation, as conditions may require.

The machine frame carrying the principal working parts, and which is adapted to have 75 a longitudinal sliding movement along the bed, comprises a motor casing 28 at the rear end thereof, a housing 29 for the head hereinafter described which carries the cutting appliances, and an intermediate casing 30, 80 the latter carrying the principal transmission gear parts. These three casings are rigidly bolted together to form a continuous machine frame, and are provided on their under faces each with guideways and suitable gib plates, which fit the guide plates 15 and 16, whereby the entire machine frame is accurately guided as a unit to travel longitudinally of the bed.

The present type of machine, as thus far 90 described, is, or may be, similar to that forming the subject matter of my pending application for mining machines, filed April 22nd, 1914, Serial No. 833,782, wherein the machine frame is adapted to be traversed under 95 power back and forth on the bed, while the cutting appliances are being operated, and wherein the bed itself may be traversed on its trucks longitudinally of the trackway, under the power of the machine. 100

It is deemed unnecessary herein to show, or to describe in detail, the mechanism for effecting the traversing of the machine upon its bed, although the mechanism for propelling the truck or bed along the trackway will 105 be hereinafter further referred to.

Referring now to the cutting appliances, and the support therefor, I have herein illus-

trated my invention as applied to a machine of the chain cutter type, the same being provided with a plurality of cutter bars, herein two, designated by the numerals 31 and 32, respectively, of common and usual construction, carrying cutter chains 33 and 34, provided, respectively with cutter-like bits 35 and 36. Preferably, the cutters of one set are arranged in staggered relation with the 10 cutters of the other set, and extend toward the spaces therebetween. Preferably, also, the cutters of one set are arranged to actually enter into the spaces between the cutters of the other set, so that they actually overlap. The advantages secured by this arrangement will presently appear.

In order to impart a cutting movement to the chains, while maintaining the described relative arrangement of the two sets 20 of cutters, the cutter bars are so mounted and the chains so driven, that a definitely timed relation between the chains is insured, regardless of the swinging motion of the cutter bars. To this end, the cutter bars 31 and 32 are provided respectively with hubs 37 and 38, swiveled in bearings 39 and 40 in a vertically movable cutter-carrying head 41, the latter being provided with guides in the form of tongues 42 and 43, mounted to 30 slide in vertical guideways 44 and 45, respectively, in the cutter head housing 29. The cutter chain 33 is herein driven by a sprocket wheel 46, and the cutter chain 34 is driven by a sprocket wheel 47 in the customary and wellknown manner. These sprocket 35 wheels are herein formed on or secured to sleeves 48 and 49, respectively, the latter being coaxially arranged with respect to the hubs 37 and 38, constituting the pivots of the cutter bars. Spur gears 50 and 51, secured to the sleeves 48 and 49, respectively, and of equal diameters, mesh with each other, and thereby cause the cutter chains to be driven in unison,—that is to say, in definitely timed relation with each other, so that as the cutter bars are swung to and fro, and as they approach each other, there shall be no interference between the two sets of cutters, but each shall enter into the spaces between the cutters of the other set.

The sleeve 48 is herein driven by a shaft 52, and since the sleeve is carried vertically by the cutter-carrying head 41, it is necessary to provide a driving connection between the sleeve and shaft, permitting such movement. To this end, the shaft may be provided with one or more, herein three, keys 53, sliding freely in keyways 54 provided in the sleeve, thus providing a splined connection between the shaft and sleeve, whereby the latter may be raised or lowered, without disturbing the driving connection, the shaft remaining in fixed position vertically.

The shaft 52 is herein driven by a beveled gear 55, secured thereto and meshing with a

beveled pinion 56, both arranged within a fixed housing 57, which latter holds the beveled gear against vertical movement. The beveled pinion 56 is herein secured to a main driving shaft 58, journaled at its forward 70 end in the housing 29 (Fig. 3) and at its rear end in the casing 30 (Fig. 3*).

To turn the shaft 58 and supply power for the other movements of the machine, a driving motor 160 in the motor casing 28 is 75 employed. The motor 160 may be of any suitable type, but is herein shown as an electric motor having an armature shaft 161 carried in bearings supported by the casing 28, there being secured to the armature shaft 80 near its forward end a driving pinion 162 meshing with a large driving gear 163, the latter arranged concentric with the axis of the main driving shaft 58. The gear 163 is splined to a sliding clutch sleeve 164 freely 85 rotatable on the shaft 58, the sleeve having clutch teeth on one side adapted to engage with similar clutch teeth on a member 165 fixed to the shaft 58. At its opposite end, the clutch sleeve 164 has similar clutch teeth 90 adapted to be engaged with and drive a sleeved member 166 mounted for free rotation upon the end of the shaft 58 and carrying a bevel driving gear 167. A clutch lever (not shown) may be utilized to move the 95 clutch sleeve 164 longitudinally. In one position, said clutch sleeve engages the driving member 165 and causes motor driven movement of the shaft 58. If moved in the opposite direction, it engages the truck driving 100 sleeve 166 and drives the gear 167, while turning loosely about the shaft 58. In the intermediate position shown in Fig. 3* both the shaft 58 and the gear 167 are disconnected from the driving motor 160.

105

The gear 167 is employed to propel the truck, and for that purpose engages a bevel gear 168, the latter mounted to turn with a shaft 169 in bearings carried by the frame of the truck or portable support 12. A bevel 110 pinion 170 is provided to turn with the gear 168 and meshes with a bevel drive gear 171, the latter mounted upon a horizontal shaft 172 which carries a bevel pinion 173 meshing with a bevel gear 174 secured to the 115 rear axle 24. Sprocket driving chains 175 (Figs. 1 and 2) impart driving movement from the rear axle 24 to the forward axle 23 on the rear truck. When the clutch sleeve 164 is moved to its rear position, the motor 120 is utilized to propel the truck through the mechanism described.

As a means for raising and lowering the cutter-carrying head, in order to enable the cutter chains to enter the vein at the desired 125 height, the cutter head is provided with an elevating and depressing mechanism preferably comprising a plurality of elevating screws 59, 60, 61 and 62. Threaded onto these elevating screws are nuts 63, 64, 65 130

and 66, all of which are shown in Fig. 4, but only the nut 66 is shown in vertical section in Fig. 3. As a means for causing all of the elevating screws and nuts to act in unison, they are herein geared together, the nuts having appropriately formed upon or secured thereto spur gears 67, 68, 69 and 70, respectively. The gears 67 and 68 mesh with a driving pinion 71, while the gears 69 and 70 mesh with a driving pinion 72, said pinions being loosely mounted on the sleeves 48 and 49 respectively.

As a means for supplying power to drive the pinions 71 and 72, the latter are provided with jaw clutches 73 and 74, which may be engaged with and disengaged from similar clutches formed on the hubs of the gears 50 and 51, respectively. It will now be evident that when the gears 50 and 51 are driven in the proper direction, they may be caused to drive the pinions 71 and 72, and thereby drive the gears 67, 68, 69 and 70, whereby the nuts 63, 64, 65 and 66, are driven in the proper direction to raise or lower the cutter-carrying head 41, as the circumstances may require. It must be evident that to accomplish this, the elevating screws must be held fixed in the base of the cutter head housing 29, while the nuts must travel vertically with the movable cutter head, the latter to that end being provided with suitable housings to receive the driving gears, that for the gear 70 being indicated at 75. The nuts are journaled in appropriate bearings, that for the nut 66 being indicated at 76, said nut being held against axial movement in its bearing by a collar 77 at its lower end, and by the gear 70 at its upper end, whereby rotation of the nut on the elevating screw enforces a vertical movement of the nut which causes the cutter-carrying head 41 to move correspondingly.

As a means for engaging the driving pinions 71 and 72 with and disengaging them from the gears 50 and 51, respectively, said pinions are herein provided with annular grooves 78 and 79 to receive a gear-shifting yoke 80, the latter having a stem 81 having appropriately formed thereon or secured thereto a rack 82, meshing with a pinion 83, by means of which the yoke may be shifted vertically to the extent necessary to engage the jaw clutches with and disengage them from each other. The pinion 83 is secured to a shaft 84, mounted in bearings 85 appropriately formed on or secured to the vertically movable cutter-carrying head 41, in order to move therewith. The clutches may be shifted manually through the described connections by means of a grasping lever 86 secured to the shaft 84, and projecting upwardly through an opening 87 to a point where it may be readily grasped by the operator.

As a means for causing discontinuance of the raising or lowering of the cutter-carrying head at a predetermined point in its travel, I have herein provided means for automatically shifting the pinions 71 and 72 out of driving engagement with the gears 50 and 51. To this end, the shaft 84 is herein provided with oppositely-extending arms 87 and 88, having jaws 89 and 90, (Fig. 7) respectively, to receive pins 91 and 92 carried by collars 93 and 94, respectively, the latter being mounted to slide vertically on rods 95 and 96. These rods terminate at their lower ends, and are fixedly secured to the base of the fixed housing 29. Secured to the rod 95 at an appropriate point thereon is a stop collar 97, adapted to be engaged by the sliding collar 93 at a suitable point in the upward travel of the cutter carrying head 41, whereby the driving pinions are shifted to discontinue the upward movement of the head, while in a similar manner, there is secured to the rod 96 at an appropriate point thereon a stop collar 98, adapted to be engaged by the sliding collar 94 during the downward travel of the head, to cause a discontinuance of the downward movement of the head.

It will now be evident that the mechanism just described prevents accidental over-travel of the head in either its upward or downward movement.

I will now describe the mechanism by means of which the cutter bars or either of them may swivel to and fro.

Secured to, and depending from, the outer bars are internal gear segments 99 and 100, the latter meshing respectively with pinions 101 and 102. These pinions are secured to shafts 103 and 104, respectively, the latter being journaled in appropriate bearings 105 and 106, carried by the vertically movable cutter head 41. In Fig. 5, the bearing 106 is shown in vertical section, and its mode of support on the cutter head 110 its clearly shown. Since the cutter head carries the shafts 103 and 104 vertically, it is necessary to provide some means for driving said shafts, while permitting such vertical movement. It will be unnecessary to describe both sets of driving connections for these shafts, since they are substantially identical, and I shall therefore describe only the driving connections for the shaft 104. The latter is herein provided with one or more, herein three, keys 107, arranged to slide freely in corresponding keyways in the sleeve 108, (Fig. 6) the latter being journaled, but held against axial movement, in a bearing 109, which latter is fixedly secured to the housing 29. As a means for driving the sleeve, two beveled gears 110 and 111 are mounted loosely thereon, and mesh with a beveled pinion 112. Either of the beveled gears may be coupled to the sleeve by the

use of a clutch member 113, adapted to slide axially thereon, but held against rotation with relation thereto by one or more, herein three, keys 114 on the sleeve, engaging corresponding keyways in the sliding clutch member. The latter is provided with jaw clutch teeth 115 adapted to interengage with clutch teeth 116 on the gear 110, and is also provided with jaw clutch teeth 117, adapted to be engaged with clutch teeth 118 on the gear 111. It will now be evident that by shifting the clutch member 113 into driving connection with one of the beveled gears, the shaft 103 may be rotated in one direction, while if the clutch member be shifted into engagement with the other gear, the shaft will be rotated in the opposite direction. As a means for shifting the clutch member, the latter is herein provided with a circumferential groove 119, to receive a clutch-shifting yoke 120. This yoke is herein secured to a rockshaft 121, extending entirely across the housing 29, and through appropriate bearings 122 and 123 at opposite sides of the latter. Hand levers 124 and 125, secured to opposite ends respectively of the shaft 121 may be utilized to rock the latter, thereby to shift the clutches. In order that either clutch may be shifted independently of the other, the clutch shifting yokes are loosely mounted on the rockshaft 121, but may be coupled thereto by the use of a manually shiftable clutch. These clutches are identical in construction, and therefore a description of that used in connection with the yoke 120 will suffice for both.

Referring now to Fig. 6, the hub of the yoke 120 is provided with clutch teeth 126 adapted to be engaged by corresponding clutch teeth 127, formed on a sliding collar 128, the latter being keyed to the rockshaft 21 by means of a key 129. As a means for shifting the collar 128, the same is herein provided with an annular groove 130, to receive a forked lever 131 having a grasping portion 132 projecting through the wall of the housing 29 to the exterior thereof, where it may be grasped by the hand of the operator. It will now be apparent that by the use of the described clutches, either of the cutter bars may be swung independently of the other, or both bars may be swung simultaneously in either direction.

The pinion 112 (see Fig. 5), is herein secured to a shaft 133, the latter being journaled in bearings 134 and 135, and having secured thereto a worm gear 136 meshing with a worm 137. It should be remembered here that the mechanism just described is duplicated at the other side of the machine, and that therefore there is another worm similar in function to the worm 137 just referred to. Both of these worms are secured to a shaft 138, the latter having also secured thereto a worm gear 139 meshing with a worm 140.

This worm is loosely mounted on a power shaft 58, but may be driven thereby through the use of appropriate connecting devices, for example a friction clutch 141 herein comprising a clutch member 142 formed on the hub of the worm 140, and a mating clutch member 143, the latter being slideable axially on the shaft, but keyed to rotate therewith by the use of the key 144.

As a means for causing driving engagement of these clutch members with each other, there is herein provided a helical compression spring 145, encircling the shaft 58, disposed in a recess 146, and bearing at one end against the inner end of said recess and at the other end against an adjustable abutment 147, appropriately secured to the shaft as by a screw thread. This clutch provides a frictional driving connection capable of slipping when the swinging cutter bars reach the limit of their travel in either direction. This driving connection may be manually interrupted at will through the use of a clutch shifting lever 148, engaging a collar 149 located in an annular groove 150 in the shiftable clutch member 143.

The described form of machine may be used for a great variety of purposes, but the specific embodiment herein shown has particular application to the cutting of kerfs at variable heights between the floor and the roof of the mine. This is often required where a dirt seam extends across the face or rib of the coal near the roof, or intermediate the roof and the floor, and it becomes necessary to cut out or remove this seam before the coal is broken down, or where for any other reason the kerf is required between the floor and the roof.

The machine may be utilized for rib cutting by laying the trackway parallel with and closely adjacent the rib on either side of the machine, and the proper cutter bar may be swung laterally from the position shown in Fig. 1 into the face of the rib, until the cutter bar stands at right angles to the longitudinal dimension of the machine, whereupon the machine frame is moved longitudinally to cause the cutter bar to be fed in a path parallel with the face of the rib.

During this cutting operation, the bed and trucks are held fixed by any suitable clamping means, such as a jack post similar to the jack post 151 represented in Fig. 2.

While the machine is capable of use for rib-cutting as just described, it has particular advantages in connection with entry cutting, and in Figs. 10 and 11. I have illustrated its application to this class of work, Fig. 10 showing one method of operation and Fig. 11 another. Herein, the trackway is laid upon the bottom of the mine near the mid-portion of the entry, and the machine is brought up on the trackway with

the forward end of its bed close to the face of the coal. With the two cutter bars projecting forwardly parallel to each other and parallel to the longitudinal median line of the machine, the frame may be fed to the forward limit of its movement upon the bed, then clamped in position, after which power is supplied to swing the cutter bars laterally in opposite directions to the proper extent, 5 whereupon their outward movement is stopped, and the machine bed retracted, until the cutter bars are entirely withdrawn from the work. The different successive positions occupied by the cutter bars during 10 the foregoing operation are marked respectively A—A, B—B, C—C and D—D in Fig. 10. Another method of operation is illustrated in Fig. 11, in which it will be observed that the cutter bars are first swung 15 laterally in opposite directions to the proper extent, they are then held fixed in such position, after which the machine frame is fed forward to the limit of its movement upon the bed; the machine is then clamped in position, after which the cutter bars are swung 20 inwardly toward each other, thus completing the cut, after which a new cut may be commenced by simply swinging the cutter bars outwardly, and advancing them as before. The different successive positions occupied by the cutter bars during the foregoing operation are indicated respectively by the letters E—E, F—F, and G—G in Fig. 25 11. The latter mode of operation is preferred to the former, because of the saving of time due to the elimination of one of the movements required in the former.

The use of the duplicate arrangement of the cutter bars has certain other distinct 30 advantages in entry cutting, among them being the rapidity of the cutting operation, and absence of lateral thrust, the latter being due to the fact that the thrust of one cutter bar equalizes that of the other. This makes 35 it possible to operate the machine without the use of any jacks to receive lateral thrust. The vertical adjustment of the cutting appliances can be performed without disturbing the position or relation of the other 40 working parts of the machine, and the vertical location of the kerf in the face or in the rib may be changed quickly and easily at any time, as may be required to suit the particular conditions met.

45 55 While I have herein shown and described one specific form or embodiment of my invention for illustrative purposes, and have disclosed and discussed in detail the construction and arrangement incidental to one 60 specific application thereof, it is to be understood that the invention is limited, neither to the mere details or relative arrangement of parts, nor to its specific embodiment herein shown, but that extensive deviations 65 from the illustrated form or embodiment of

the invention may be made, without departing from the principles thereof.

Having thus described my invention, what I claim and desire by Letters Patent to procure is:

70

1. In a mining machine, a support movable toward and from the work, and a pair of cutting devices on said support and movable between a separated position and a position of adjacent parallelism in which the cuts made thereby are substantially joined.

2. In a mining machine, a support movable toward and from the work, and a pair of swinging cutting devices movable thereon between a diverging position and a position of adjacent parallelism in which the cuts made thereby are substantially joined.

80

3. In a mining machine, a pair of cutting devices, means whereby said cutting devices may be moved toward and from the work, and means for moving said cutting devices between a separated position and a position of adjacent parallelism in which the cuts made thereby are substantially joined.

90

4. In a mining machine, a pair of swinging cutting devices, means whereby said cutting devices may be moved toward and from the work, and means for moving said cutting devices between a diverging position and a position of adjacent parallelism in which the cuts made thereby are substantially joined.

95

5. In a mining machine, a frame, a pair of cutter bars movably mounted on said frame, movable cutter chains on said bars, means whereby said frame may be moved toward and from the work, and means for moving said cutter bars between a separated position and a position of adjacent parallelism in which the cuts made thereby are substantially joined.

100

6. In a mining machine, a frame, a pair of swinging cutter bars pivoted thereon, movable cutter chains on said bars, means whereby said frame may be moved toward and from the work, and means for moving said cutter bars between a diverging position and a position of adjacent parallelism in which the cuts made thereby are substantially joined.

105

7. In a mining machine, a pair of cutting devices, means for operating said cutting devices, means whereby said cutting devices may be moved toward and from the work while in operation, means for moving said cutting devices between a separated position and a position of adjacent parallelism in which the cuts made thereby are substantially joined while continuing their operation, a motor, and connections between said motor and said cutter operating means and moving means for actuating both of said means.

110

8. In a mining machine, a truck provided

125

130

- with ways, a frame movable on said ways, a pair of cutting devices on said frame, means for operating said cutting devices, and means for moving said cutting devices 5 on said frame between a separated position and a position of adjacent parallelism in which the cuts made thereby are substantially joined while continuing their operation.
- 10 9. In a mining machine, a support movable toward and from the work, a second support movable on said first named support in a direction longitudinal to the movement thereof, and a pair of cutting devices on said 15 second support and movable thereon between a separated position and a position of adjacent parallelism in which the cuts made thereby are substantially joined.
10. In a mining machine, the combination 20 of a pair of cutting devices each provided with a set of spaced cutters, the cutters of one set being arranged to enter into the spaces between the cutters of the other set; means for moving said cutting devices one 25 toward and from the other; and means for imparting a cutting movement to said devices while insuring the continuance of the relative arrangement of the cutters of the two sets so that the cutters of one set shall 30 enter into the spaces between the cutters of the other set when said devices are moved one toward the other.
11. In a mining machine, the combination 35 of a pair of cutter bars; a pair of cutter chains carried thereby and provided each with a set of spaced cutters, the cutters of one set being arranged to enter into the spaces between the cutters of the other set; means for moving said cutter bars one to 40 ward and from the other; and means for driving said cutter chains while insuring a definitely timed relation therebetween so that the cutters of one set shall enter into the spaces between the cutters of the other 45 set when said bars are moved one toward the other.
12. In a mining machine, the combination 50 of a pair of cutter bars, movable toward and away from one another, a pair of cutter chains carried thereby and provided each with a set of spaced cutters, the cutters of one set being arranged in staggered relation with the cutters of the other set and extending toward the spaces therebetween; and 55 means for driving said cutter chains while maintaining a definitely timed relation therebetween so that the cutters of one set shall be opposite the spaces between the cutters of the other set when said cutter bars 60 are moved one toward the other.
13. In a mining machine, a frame, a pair 65 of swinging cutter bars pivoted thereon immediately adjacent to one another and movable into parallel relation, cutter chains on said bars having cutter bits bridging the

gap between said bars when the same are in parallel relation, means for swinging said bars from diverging to parallel relation, and means for operating said cutter chains.

14. A mining machine comprising, in 70 combination, two cutter frames each provided with its cutter chain, swinging means for swinging said cutter frames contemporaneously in opposite directions respectively, a single motor, and means for driving 75 said cutter chains and swinging means from said motor.

15. A mining machine comprising, in combination, two pivoted cutter frames each provided with a cutter chain, and means for 80 swinging said frames contemporaneously in opposite directions respectively and simultaneously operating said chains including a motor operatively connected both to one of said frames and its chain. 85

16. A mining machine comprising, in combination, two cutter frames each provided with its cutter chain, swinging means for swinging said cutter frames contemporaneously in opposite directions, a single 90 motor, means for driving said cutter chains and swinging means therefrom, and disconnecting means for operatively disconnecting one of said cutter frames from said motor. 95

17. In a mining machine, a truck, a plurality of pivoted cutter bars thereon, endless cutter chains carried on said bars, means for swinging said bars from diverging relation in opposite directions toward one another, 100 means for operating said chains, truck driving means, a single motor, and driving means operatively connected between each of said several means and said motor.

18. In a mining machine, a pair of cutting 105 devices, means for operating said cutting devices, means whereby said cutting devices may be moved toward and from the work while in operation, means for bodily moving said cutting devices in opposite directions 110 respectively and in a direction transverse to their first named movement while continuing their operation, a motor, and connections between said motor and said cutter operating means and moving means for actuating 115 both of said means.

19. In a mining machine, a pair of swinging cutting devices, means for operating said cutting devices, means whereby said cutting devices may be moved toward and from the 120 work while in operation, means for swinging said cutting devices toward and from each other while continuing their operation, a motor, and connections between said motor and said cutter operating means and swinging means for actuating both of said means. 125

20. In a mining machine, a pair of pivoted cutter bars, endless chains on said cutter bars each provided with a set of cutter bits, means for driving said chains in timed rela-

- tion, means whereby said cutter bars may be moved toward and from the work while said chains are in operation, means for swinging said cutter bars on their pivots between a 5 diverging position and a position of parallelism with the cutter bits of one set entering the spaces between the cutter bits of the other set while continuing the operation of said chains, a motor, and driving connections between said motor and said chain driving and bar swinging means for actuating both of said means.
21. In a mining machine, a truck provided with ways, a frame movable on said ways, a 15 pair of cutting devices on said frame, means for operating said cutting devices, means for moving said cutting devices on said frame in opposite directions respectively while continuing their operation, and a single motor and connections for actuating said cutter operating and moving means.
22. In a mining machine, a vertically movable support, means for raising and lowering it, a pair of cutting devices on said 25 support, means for operating said cutting devices, means whereby said cutting devices may be moved toward and from the work while in operation, means for moving said cutting devices in opposite directions respectively and in a direction transverse to their
- first named movement while continuing their operation, a motor, and connections between said motor and said cutter operating means, said moving means, and said raising and lowering means for actuating all 35 of said means.
23. In a mining machine, a truck provided with ways, a frame movable on said ways, a pair of cutting devices on said frame, means for operating said cutting devices, and 40 means for moving said cutting devices on said frame in opposite directions, respectively, while continuing their operation.
24. In a mining machine, truck provided with ways, a frame horizontally movable on 45 said ways, a support vertically movable on said frame, means for raising and lowering said support, a pair of cutting devices on said support, means for operating said cutting devices, and means for moving said cutting devices on said support in opposite directions, respectively, while continuing their operation.

In testimony whereof I have signed my name to this specification in the presence of 55 two subscribing witnesses.

MORRIS P. HOLMES.
